Primary Examiner — Cynthia R Underwood(57) **CLAIM**

The ornamental design for a fold drawer slide, as shown and described.

DESCRIPTION

FIG. 1 is a top, front, left side perspective view of a fold drawer slide, showing my new design;
FIG. 2 is a bottom, rear, right side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an alternative perspective view of the fold drawer slide in use;
FIG. 10 is an enlarged view of the portion labeled “10” framed in FIG. 1;
FIG. 11 is an enlarged view of the portion labeled “11” framed in FIG. 1;
FIG. 12 is an enlarged view of the portion labeled “12” framed in FIG. 9; and,
FIG. 13 is an enlarged view of the portion labeled “13” framed in FIG. 9.
The broken lines form the boundaries of the enlargements and form no part of the claim. The broken away symbols indicate that any portion of the article beyond what is shown forms no part of the claim.

1 Claim, 13 Drawing Sheets(56)
